AUTOMATIC FIREARM CONSTRUCTION

David M. Williams, New Haven, Conn., assignor
to Western Cartridge Company, New Haven,
Conn., a corporation of Delaware

Application September 22, 1941, Serial No. 411,776

4 Claims. (CL 42—3)

The present invention relates to improvements in firearms of the type wherein the energy developed by the discharge of the firearm is utilized to open the breech-bolt and extract the just-fired cartridge, preparatory to the firearm being again loaded and discharged.

More particularly, the present invention relates to improvements in a construction and arrangement of parts (including a breech-closing spring) whereby the breech-bolt of an automatic firearm is returned toward its breech-closing position, following the automatic retirement of the said breech-bolt as an incident to the discharge of the firearm.

One of the objects of the present invention is to provide a superior automatic firearm construction wherein the breech-closing means may be disassembled from the firearm for inspection, cleaning, repair and replacement.

A further object of the present invention is to provide a superior automatic firearm construction wherein the breech-closing means may be provided at a low cost for the parts and at a low cost for assembly.

With the above and other objects in view, as will appear to those skilled in the art from the present disclosure, this invention includes all features in the said disclosure which are novel over the prior art.

In the accompanying drawings, in which certain modes of carrying out the present invention are shown for illustrative purposes:

Fig. 1 is a broken view mainly in vertical central-longitudinal section and partly in side elevation of the central portion of an automatic firearm embodying the present invention;

Fig. 2 is a longitudinal sectional view taken on the line 2—2 of Fig. 1;

Fig. 3 is a transverse sectional view taken on the line 3—3 of Fig. 1;

Fig. 4 is a transverse sectional view taken on the line 4—4 of Fig. 1;

Fig. 5 is a broken view of the structure mainly in reverse plan with a portion of the receiver in section and showing the breech-closing plunger in released position for removal from or introduction into the firearm;

Fig. 6 is a detached view of the receiver in side elevation;

Fig. 7 is a view in front elevation of the receiver;

Fig. 8 is a broken perspective view of the forward portion of the action-slide detached; and

Fig. 9 is a perspective view of the breech-closing plunger detached.

The particular gas-operated automatic firearm herein chosen for purposes of illustration includes in the main a receiver 10, a barrel 11, a stock 12 and a barrel-cover 13. The stock 12 and barrel-cover 13 are preferably formed of wood or other heat-insulating material and both thereof are related to the receiver 10 and barrel 11 in a manner generally common in the art of military firearms.

The barrel 11 projects forwardly from and is rigidly attached at its rear to the forward portion of the receiver 10. Furthermore, the said barrel is provided with an axial bore 14 and is formed with an integral depending lug 15 located forwardly of the receiver 10 and accommodated in an upwardly-opening clearance-cavity 16 formed in the stock 12. Leading downwardly and rearwardly from an intermediate portion of the bore 14 in the barrel 11 and in the lug 15 is a gas-passage 17 intersecting at its lower end the forward end of a rearwardly-opening piston-chamber 18 formed in the said lug 15.

Reciprocating in the piston-chamber 18 in the lug 15 above described is a piston generally designated by the reference character 20 and including a cylindrically-contoured head 21 at its forward end and a rearwardly-projecting cylindrically-contoured stem 22. The stem 22 just referred to reciprocates in a ring-like piston-retainer 23 threaded within the rear end of the piston-chamber 18 in the lug 15. At its rear end the stem 22 of the piston 20 is normally in contact with the forward face of the rear wall of the U-shaped head 24 of an action-slide generally designated by the reference character 25 (Fig. 8).

In addition to the head 24 above referred to, the action-slide 25 also includes a thrust-bar 26 extending rearwardly from the said head alongside of and in parallelism with the right side of the barrel 11 and the right side of the receiver 10. At its rear end the thrust-bar 26 is formed with an integral operating-handle or finger-piece 27 and with an integral lug 28. In its inner face, just forwardly of its operating-handle 27, the thrust-bar 26 is formed with a recess 29 formed partly in the lug 28 and into which fits a laterally-extending lug 30 forming a feature of a breech-bolt 31 oscillating and reciprocating in the receiver 10.

The recess 29 in the action-slide 25, as well as the lug 30 and the breech-bolt 31, requires no elaborate description or illustration herein other than to state that their relationship and opera-

tion is along the same line as that employed in the well-known Garand military rifle.

In the right side of its rear face, the head 24 of the action-slide 25 is provided with a rearwardly-opening conically-contoured socket or seat 32 (Fig. 8) normally receiving the conically-contoured forward end of a breech-closing plunger 33 provided about midway of its length with a knurled or otherwise roughened finger-gripping portion 34 for purposes as will herein-after appear.

At its rear the breech-closing plunger 33 is reduced in diameter to provide a stem 35 and a rearwardly-facing spring-seat 36. The said stem 35 of the breech-closing plunger 33 is encircled by the forward end of a helical breech-closing spring 37. The said breech-closing spring 37 is housed within a forwardly-opening cylindrically-contoured spring-receiving recess 38 formed in the right side-wall of the receiver 10 in a plane below the center-line of the barrel 11. The said breech-closing spring 37 thrusts at its rear end against the rear end-wall of the spring-receiving recess 38 and thrusts at its forward end against the rearwardly-facing spring-seat 36 of the breech-closing plunger 33 in such manner as to normally maintain the conically-contoured forward end of the said plunger in engagement with the socket or seat 32 in the head 24 of the action-slide 25. Leading laterally from and partly intersecting the side of the socket or seat 32 in the head 24 of the action-slide 25 is a longitudinally-inclined transversely-curved lead-in surface or clearance-groove 39 for purposes as will herein-after appear.

It is to be noted by reference to Figs. 1 and 2 in particular that when the action-slide 25 is in its normal forward position, the spring-seat 36 of the breech-closing plunger 33 is located slightly forwardly of the open forward end of the spring-receiving recess 38 in the receiver 10. Preferably, the diameter of the breech-closing plunger 33 is such as to provide a really-free sliding-fit within the plunger-receiving recess 38 of the receiver 10.

When the firearm is discharged, the gases created by the discharge will pass downwardly through the gas-passage 17 into the piston-chamber 18 in the lug 16, with the result that the piston 20 will be rapidly impelled rearwardly until the rear face of its head 21 engages with the forward face of the piston-seat 22. The rapid movement of the piston 20 will "kick" so to speak, the entire action-slide 25 rearwardly against the tension of the breech-closing spring 37, with the effect of unlocking the breech-bolt 81 and moving the same rearwardly to extract the just-fired cartridge in a manner generally common in automatic firearms.

When the action-slide 25 reaches the limit of its rearward travel under the impetus imparted to it by the discharge of a cartridge, the breech-closing spring 37, acting through the breech-closing plunger 33, will normally return the action-slide 25 to its forward position in which it is shown in Figs. 1 and 2, to thereby insert a fresh cartridge into the rear end of the barrel 11, preparatory to another discharge of the firearm, all in a manner well known in the art and not requiring detailed description herein.

After the stock 12 and barrel-cover 13 are removed and should it then be desired to dismount the breech-closing plunger 33 and its complementary breech-closing spring 37 from the firearm-structure, the user of the firearm has but to grasp the said plunger 33 by means of its finger-

gripping portion 34 and force the same slightly rearwardly, to free its forward end from engagement with the seat or socket 32 in the action-slide 25, whereupon the forward end of the said plunger 33 may be swung outwardly clear of the action-slide and permitted to move forwardly through the clearance-groove 39, under the urge of the breech-closing spring 37, as is shown in Fig. 5. The breech-closing plunger 33 and the breech-closing spring 37 may now be completely removed from the firearm-structure, preparatory to disassembling other features of the firearm-structure if desired. It is possible to swing the breech-closing plunger 33 as above described by virtue of the fact that the rearwardly-projecting stem 35 thereof is sufficiently small in diameter to permit such action.

When it is desired to reinstall the breech-closing spring 37 and the breech-closing plunger 33, the said parts may be first placed in the firearm-structure in substantially the positions in which they are shown in Fig. 5. The user of the firearm may now first force the breech-closing plunger 33 rearwardly against the tension of the spring 37 by grasping the knurled finger-gripping portion 34 of the said plunger. It is preferred that during the manual process of forcing the plunger 33 rearwardly, inward pressure upon its forward end should be simultaneously exerted so that when the conically-contoured forward end of the said plunger comes into registry or substantial registry with the side wall of the socket or seat 32, the forward end of the said plunger may be snapped inwardly for full engagement with the said socket or seat 32, as shown in Figs. 1 and 2.

The lead-in surface 39 in the side of the head 24 of the action-slide 25 serves to guide the forward end of the breech-closing plunger 33 gradually outwardly as the said plunger moves forwardly in the act of dismounting the same from the firearm-structure. Conversely, the said lead-in surface 39 provides for the gradual lateral inward travel of the forward end of the plunger 33 as the same is moved rearwardly in the act of reinstalling the said plunger in the firearm-structure.

The invention may be carried out in other specific ways than those herein set forth without departing from the spirit and essential characteristics of the invention, and the present embodiments are, therefore, to be considered in all respects as illustrative and not restrictive, and all changes coming within the meaning and equivalency range of the appended claims are intended to be embraced therein.

I claim:

1. An automatic firearm construction including in combination: a barrel; a receiver extending rearwardly from the said barrel and formed with a forwardly-opening spring-receiving socket; a reciprocating action-slide slidably associated with the said barrel and the said receiver and having a transverse portion exterior of the said receiver and spaced forwardly of and extending crosswise of the open forward end of the spring-receiving socket in the said receiver, the said transverse portion being formed with a rearwardly-opening plunger-receiving socket for the reception of the forward end of a breech-closing plunger; a helical breech-closing spring located in the forwardly-opening spring-receiving socket in the said receiver; and a breech-closing plunger having its forward end normally releasably seated in the rearwardly-opening plunger-receiving socket in the transverse portion of the said action-slide

and having its rear portion engaged with the forward portion of the said breech-closing spring and extending into the forward portion of the spring-receiving socket in the said receiver with a free sliding fit with capacity for being laterally tilted therein to permit the forward end of the said plunger to be laterally displaced out of engagement with the plunger-receiving socket in the said action-slide to permit the forward removal of the said breech-closing plunger from the firearm-structure.

2. An automatic firearm construction including in combination: a barrel; a receiver extending rearwardly from the said barrel and formed with a forwardly-opening spring-receiving socket; a reciprocating action-slide slidably associated with the said barrel and the said receiver and having a transverse portion exterior of the said receiver and spaced forwardly of and extending crosswise of the open forward end of the spring-receiving socket in the said receiver, the said transverse portion being formed with a rearwardly-opening plunger-receiving socket for the reception of the forward end of a breech-closing plunger; a helical breech-closing spring located in the forwardly-opening spring-receiving socket in the said receiver; and a breech-closing plunger having its forward end normally releasably seated in the rearwardly-opening plunger-receiving socket in the transverse portion of the said action-slide, the said plunger being formed at its rear with a relatively-slender stem fitting within the forward end of the said helical breech-closing spring and extending into the forward portion of the spring-receiving socket in the said receiver and together with the forward portion of the said breech-closing spring having a free sliding fit in the forward portion of the spring-receiving socket in the said receiver with capacity for being laterally tilted therein to permit the forward end of the said plunger to be laterally displaced out of engagement with the plunger-receiving socket in the said action-slide to permit the forward removal of the said breech-closing plunger from the firearm-structure.

3. An automatic firearm construction including in combination: a barrel; a receiver extending rearwardly from the said barrel and having a mechanism-receiving chamber therein and formed in a wall-portion to one side of the said mechanism-receiving chamber with a spring-receiving socket intersecting the forward end of the receiver; a reciprocating action-slide slidably associated with the said barrel and the said receiver and having a transverse portion spaced forwardly of the forward end of the said receiver and extending crosswise of the open forward end of the spring-receiving socket therein, the said transverse portion being formed with a rear-

wardly-opening plunger-receiving socket for the reception of the forward end of a breech-closing plunger; a helical breech-closing spring located in the forwardly-opening spring-receiving socket in the wall portion of the said receiver; and a breech-closing plunger having its forward end normally releasably seated in the rearwardly-opening plunger-receiving socket in the transverse portion of the said action-slide and having its rear portion engaged with the forward portion of the said breech-closing spring and extending into the forward portion of the spring-receiving socket in the said receiver with a free sliding fit with capacity for being laterally tilted therein to permit the forward end of the said plunger to be laterally displaced out of engagement with the plunger-receiving socket in the said action-slide to permit the forward removal of the said breech-closing plunger from the firearm-structure.

4. An automatic firearm construction including in combination: a barrel; a receiver extending rearwardly from the said barrel and having a mechanism-receiving chamber therein and formed in a wall portion to one side of the said mechanism-receiving chamber with a spring-receiving socket intersecting the forward end of the receiver; a reciprocating action-slide slidably associated with the said barrel and the said receiver and having a transverse portion spaced forwardly of the forward end of the said receiver and extending crosswise of the open forward end of the spring-receiving socket therein, the said transverse portion being formed with a rearwardly-opening plunger-receiving socket for the reception of the forward end of a breech-closing plunger; a helical breech-closing spring located in the forwardly-opening spring-receiving socket in the wall portion of the said receiver; and a breech-closing plunger having its forward end normally releasably seated in the rearwardly-opening plunger-receiving socket in the transverse portion of the said action-slide, the said plunger being formed at its rear with a relatively-slender stem fitting within the forward end of the said helical breech-closing spring and extending into the forward portion of the spring-receiving socket in the said receiver and together with the forward portion of the said breech-closing spring having a free sliding fit in the forward portion of the spring-receiving socket in the said receiver with capacity for being laterally tilted therein to permit the forward end of the said plunger to be laterally displaced out of engagement with the plunger-receiving socket in the said action-slide to permit the forward removal of the said breech-closing plunger from the firearm-structure.

DAVID M. WILLIAMS.
